UNITED STATES PATENT OFFICE.

MAX J. RUDERT, OF REDLANDS, CALIFORNIA.

PHONOGRAPH-NEEDLE.

1,358,178.

Specification of Letters Patent.

Patented Nov. 9, 1920.

Application filed April 8, 1919. Serial No. 288,563.

To all whom it may concern:

Be it known that I, MAX J. RUDERT, a citizen of the United States, residing at Redlands, in the county of San Bernardino, State of California, have invented new and useful Improvements in Phonograph-Needles, of which the following is a specification.

This invention relates to needles for phonograph machines; and the object of the invention is to provide a phonograph needle which will give improved reproduction results and will have a long operating life, and will not damage the record. It is a further object to provide a needle which is adjustable for loud and soft reproduction; and to provide such a needle in simple, inexpensive and easily manufactured form.

I provide a needle construction which embodies a fine wire forming the needle proper—forming the reproducing point—such wire being in an adjustable mounting, so that the fine wire needle may be extended out of, or retracted into, its holder to adjust the projecting length of needle and thereby to vary the loudness and softness of tone and also to advance the needle from time to time to take care of wear. This advancement to take care of wear I find to be very slight; a quarter inch length of needle suffices for many hundred reproductions.

The holder in which the needle proper is held embodies a simple easily manipulated device having a shank adapted to be held in any ordinary sound box clamp. The details of this holder and the detailed features of my invention, together with other objects thereof, will be most clearly apparent from the following specific description of a specific preformed form of needle, reference being had for this purpose to the accompanying drawings in which—

Figure 1 is an enlarged elevation of the needle showing the needle proper in its position of first insertion in the holder; Fig. 2 is a longitudinal section of the needle; Fig. 3 is a view showing the needle proper; Fig. 4 is a further enlarged view of the record-following-end of the needle; and Fig. 5 is an enlarged section taken as indicated by line 5—5 on Fig. 2.

I utilize a needle wire, which I term the needle proper, as shown at 10. This needle wire is about 0.006" in diameter; and in using a small needle of this character I find that it is not necessary to sharpen the

record following end, it being only necessary to somewhat round off the end or round the end edge as is indicated at 11 in Fig. 4. And I find that this rounded edge formation is maintained by wear of the needle in the record groove; that is, as the needle wears away its end keeps about the form shown in Fig. 4.

This needle proper is mounted in a holder 12 which is provided with a shank 13 adapted to be inserted and clamped in the needle clamp of any ordinary sound box. Shank 13 forms a part of the holder body 14; this body being a cylindrical metal member preferably of steel and having at 15 a collar against which one end of an internally threaded rotatable sleeve 16 bears. Sleeve 16 may have a knurled collar 17 to facilitate manual rotation of the sleeve.

At its forward end the body 14 is conical as shown at 18, and a conical cap 19 fits over the forward end of the body, being preferably pressed onto the body, but it may be secured on the body in any suitable manner. Cap 19 has a needle aperture 20 of just the right size to pass the needle 10 and hold the needle against any loose motion, at the same time allowing the needle 10 to move freely longitudinally through the cap. Body 14 has a narrow longitudinal slot or groove 21 whose bottom 22 is preferably semi-cylindrical and registers accurately with the needle aperture 20 in cap 19; so that the inner part of needle 10 will rest against the bottom of the groove as is clearly shown in Figs. 2 and 5. The inner end of the needle has a flat lug or plate 23 secured to it, this plate being of proper thickness to fit more or less snugly in groove 21 and having a serrated edge 24 which engages with the screw-threads 25 of sleeve 16. Lug 23 may be formed by stamping or any other similar operation and may then be secured to the needle 10 by brazing, sweating or soldering, or in any other suitable manner. The lug 23 may also be provided with a handle 26 formed integrally therewith and connected thereto by a narrow neck 27; handle 26 affording ready means for handling the needle to insert it in the holder and being then broken off when the needle has been inserted in the position shown in Fig. 1. The needle may then be advanced or retracted by rotation of sleeve 16.

Fig. 2 shows the needle fully extended;

Fig. 1 shows the needle extended only a small distance. The amount of needle extension may be varied to suit the loudness or softness of reproduction desired. If the 5 needle is extended only a short distance the maximum loudness is obtained, and if the needle is extended farther, a softer reproduction will be obtained. As the needle wears away by use it may be extended from 10 time to time. This wear is extremely slight and a needle wire of an effective length of about $\frac{1}{4}$ " or $\frac{3}{8}$ " I find will last a very long time. The wire itself, although it may be harder or softer as conditions may require, 15 I prefer to make not excessively hard and not very soft.

Having described a preferred form of my invention, I claim:

1. A phonograph needle comprising a 20 body provided with a shank adapted to be secured in a sound box clamp and having a longitudinal groove extending through one end thereof, an internally threaded sleeve 25 rotatably supported on the body and extending across said groove therein, and a wire within the groove provided with a laterally projecting lug that engages the thread on said sleeve.

2. A phonograph needle comprising a 30 body adapted to be attached to a sound box and provided with a longitudinal groove extending through one end thereof, a cap fitted over said end of the body with an aperture 35 in alignment with the groove, an internally threaded rotatable sleeve surrounding the body, and a wire extending through the aperture in the cap into said groove and provided within the sleeve with a laterally projecting lug that engages the thread on 40 the sleeve.

3. A phonograph needle comprising a substantially cylindrical body, a shank adapted to be clamped in the sound box clamp and having a collar midway its ends, the end of 45 the body opposite the shank being conical, and the body having a longitudinal groove extending from the conical end to a point behind the collar, a rotatable internally

threaded sleeve surrounding the body and bearing at one end against the collar, a conical cap fitted upon the conical end of the body and confining the rotatable sleeve, said cap having a central needle aperture registering with the bottom part of said groove, a needle wire with its inner end lying in the 50 groove and its outer end projecting through the needle aperture, and a lug on the inner end of the needle with an edge engaging said threads.

4. A phonograph needle comprising a 55 body provided at one end with a shank adapted to be secured in a sound box clamp and having a longitudinal groove extending through the other end of the body and also opening laterally through the shank, a sleeve 60 rotatable on the body, and a wire in said groove provided with means engaging the sleeve, whereby it will be moved longitudinally as said sleeve is rotated.

5. In a phonograph needle, the combination 70 of a body, a sleeve surrounding the body, and a wire extending beyond one end of the body and having means engaging the sleeve, whereby it is connected to the body by the sleeve and may be fed longitudinally 75 by movement of the sleeve.

6. In a phonograph needle, the combination 80 of a body, an interiorly threaded sleeve rotatably surrounding the body, and a wire adapted to move longitudinally of the body and having at one end a lateral projection terminating in a serrated edge which engages the thread on said sleeve, for the purpose described.

7. A phonograph needle embodying a suitable 85 length of fine wire pointed at one end and having at its other end a thin, fin-like, lateral projection, the edge of which remote from the body of the wire is serrated.

In witness that I claim the foregoing I 90 have hereunto subscribed my name this 14th day of February, 1919.

MAX J. RUDERT

Witness:

V. BERNINGER.
